DESIGN FOR A SMOKER'S STAND

Charles Gloring, Los Angeles, Calif., assignor to Earl Cohen, Los Angeles, Calif.

Application August 15, 1933. Serial No. 49,033

Term of patent 3½ years

To all whom it may concern:

Be it known that I, CHARLES GLORING, a citizen of Russia, residing at Los Angeles, in the county of Los Angeles and State of California, have invented a new, original, and ornamental Design for a Smoker's Stand, of which the following is a specification, reference being had to the accompanying drawing, forming a part thereof.

Fig. 1 is a side elevational view of a smoker's stand showing my new design.

Fig. 2 is a top plan view.

Fig. 3 is a horizontal section taken on the line 3—3 of Fig. 1 and looking down upon the base portion of the smoker's stand.

I claim:

The ornamental design for a smoker's stand as shown.

CHARLES GLORING.
